UNITED STATES PATENT OFFICE.

THEODORE B. MYERS, OF ST. PAUL, MINNESOTA.

DESIGN FOR A SPOON.

SPECIFICATION forming part of Design No. 21,894, dated October 11, 1892.

Application filed August 11, 1892. Serial No. 442,814. Term of patent 3½ years.

To all whom it may concern:

Be it known that I, THEODORE B. MYERS, residing at St. Paul, Ramsey county, Minnesota, have invented and produced a new and original Design for a Spoon, of which the following is a specification, reference being had to the accompanying drawing, illustrating the same.

The drawing shows a plan view of the spoon, fully illustrating my design.

The outline of the spoon-handle is undulating or wave-like, as shown, with a beaded edge, near the top or ends the beads being in-turned in hook shape and with scalloped ornate-
ments near the tip of the handle. Along the shank of the handle, projecting inward from the beaded edge, are leaf-like representations with a space between. In the wider part of the handle is represented a view of a timbered gorge or ravine with a water-fall pouring through the same, a sky scene

in the background, the foreground below representing the channel of the stream, and the waters flowing along the same from the water-fall. In the bowl of the spoon is represented a rough rocky elevation, from the crest of which spouts a geyser.

The leading features of the design are the described ornamentations on the handle of the spoon, including within the same a water-fall and the representation of a geyser in the bowl of the spoon.

What I claim is—

The design for a spoon, substantially as herein shown and described. 35

In testimony whereof I have hereunto set my hand this 5th day of August, 1892.

THEODORE B. MYERS.

In presence of—

T. D. MERWIN,

H. S. JOHNSON.
